UNITED STATES PATENT OFFICE.

RUPERT E. ZEARFOSS, OF KEOTA, IOWA.

HEN'S NEST.

SPECIFICATION forming part of Letters Patent No. 634,051, dated October 3, 1899.

Application filed June 3, 1899. Serial No. 719,265. (No model.)

To all whom it may concern:

Be it known that I, RUPERT E. ZEARFOSS, a citizen of the United States, residing at Keota, in the county of Keokuk and State of Iowa, 5 have invented a new and useful Hen's Nest, of which the following is a specification.

My invention relates to nests for fowls, and has for its object to provide an improved nest which shall be self-closing when the 10 fowl enters, thereby preventing the entrance of other fowls while the nest is occupied.

With this object in view my invention consists in the improved construction, arrangement, and combination of parts hereinafter 15 fully described and afterward specifically pointed out in the appended claims.

In order to enable others skilled in the art to which my invention most nearly appertains to make and use the same, I will now 20 proceed to describe its construction and operation, reference being had to the accompanying drawings, forming part hereof, in which—

Figure 1 is a perspective view of a nest 25 constructed in accordance with my invention open and ready for the entrance of the hen or other fowl. Fig. 2 is a vertical sectional view of the same. Fig. 3 is a view in front elevation of the nest closed, the spring and 30 latch being shown in dotted lines.

Like letters of reference mark the same parts wherever they occur in the various figures of the drawings.

Referring to the drawings by letters, A indicates a box of suitable size and preferably 35 provided with a sloping roof or top B. In the front C is slidably secured a door D, having a hole E near its lower end.

F indicates a shallow box hinged to the 40 front at G and having its rear end suspended by a spring H, the straw or other cushioning material, as at I, being placed in such box.

J indicates a wire bail-shaped latch rigidly 45 secured at its ends in the sides of the box F, extending upward and provided with a bent forward projection K in its upper cross-bar, adapted to be seated in the hole E when the door is raised and the nest in its normal position, as in Figs. 1 and 2, thereby holding 50 the door in its raised or open position.

The parts being in their normal position, as stated, the fowl passing into the box and occupying the nest will press the inner or rear end of the nest downward, the spring 55 being only of sufficient strength to support

the unoccupied nest. This motion of the box F on its hinges will cause the bail to move inward at the top, drawing the projection K out of the hole E and permitting the door to drop to its closed position, thus in- 60 closing the fowl in the box A and securing it against the intrusion of other fowls.

The simplicity, efficiency, and advantages of the invention will be readily understood from the foregoing description. 65

While I have illustrated and described what I consider to be the best means now known to me for carrying out my invention, I do not wish to be understood as restricting myself to the exact forms and constructions shown, as many 70 slight changes therein or variations therefrom might suggest themselves to the ordinary mechanic, all of which would be clearly included within the limit and scope of my invention. 75

Having thus fully described my invention, what I claim as new, and desire to secure by Letters Patent of the United States, is—

1. The combination in a nest for hens or other fowls of an outer box provided with a 80 self-closing door, an inner hinged box yieldingly supported and a latch secured to the inner box and holding the door open when the inner box is raised, and releasing it when lowered, substantially as described. 85

2. The combination in a nest for hens or other fowls, of an outer box having a sliding door, an inner box hinged at one end and yieldingly supported at the other, and a latch secured to the inner door in position to engage and hold the door raised, when the box is elevated, and release it when depressed, substantially as described. 90

3. The herein-described nest comprising the outer box, the vertically-slidable door in the 95 front thereof having an opening near its lower end, the inner box hinged at one end to the front of the outer box below the door, the spring suspending the inner end of the inner box, and the bail-shaped latch rigidly secured 100 at its ends to the sides of the inner box near its hinges and having a projection from its upper cross-bar adapted to engage in the opening in the door when the door and inner box are raised, substantially as described. 105

RUPERT E. ZEARFOSS.
